CLAIM

The ornamental design for a children's kitchen, as shown and described.

DESCRIPTION

FIG. 1 is a front-left-top perspective view of a first embodiment of a children's kitchen showing my new design; FIG. 2 is a rear-left-top perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines are shown on an entirely claimed surface and are included to show the outlines of features that form no part of the claimed design.

1 Claim, 7 Drawing Sheets(56)
